United States Patent

Des. 242,222

Patented Nov. 9, 1976

242,222

JAR

Floyd E. Pettengill, Lancaster, Ohio, assignor to General Foods Corporation, White Plains, N.Y.

Filed Apr. 14, 1975, Ser. No. 567,462

Term of patent 14 years

Int. Cl. D9—01

U.S. Cl. D9—58

FIG. 1.

FIG. 2.

FIG. 3.

FIG. 1 is a side elevational view of a jar showing my new design, the opposite side being plain and unornamented;

FIG. 2 is a top plan view; and

FIG. 3 is a bottom plan view thereof.

The oval panel seen in FIG. 1 is recessed and the ornamentation therein is embossed.

I claim:

The ornamental design for a jar, as shown and described.
